UNITED STATES PATENT OFFICE.

FREDERIC E. BAGER, OF WINTHROP HARBOR, ILLINOIS, ASSIGNOR TO FREDERICK C. AUSTIN, OF CHICAGO, ILLINOIS.

EXCAVATOR-BUCKET CLEANER.

1,171,015.

Specification of Letters Patent.

Patented Feb. 8, 1916.

Application filed January 16, 1914. Serial No. 812,515.

To all whom it may concern:

Be it known that I, FREDERIC E. BAGER, a citizen of the United States of America, and resident of Winthrop Harbor, Lake county, Illinois, have invented a certain new and useful Improvement in Excavator-Bucket Cleaners, of which the following is a specification.

My invention relates to excavators of 10 that kind in which a series of excavating buckets are arranged to travel up and down in the trench or ditch.

It relates more particularly to excavators 15 of this kind in which the said buckets are open at front and rear, whereby each bucket receives the load at the mouth thereof, while traveling at the bottom of the ditch or trench, and then discharges the load while turning upside down at a point above.

20 My invention relates more especially, moreover, to excavators of this particular character in which a cleaner is disposed in position to pass through the buckets, to force the contents therefrom, whereby each 25 bucket is effectively cleaned while turning upside down to discharge its load.

The object of my invention is to provide 30 a novel construction and arrangement whereby the spring held rod or endwise reciprocating member for yieldingly holding the cleaner in position is relieved of side thrust, and is subject only to endwise thrust, whereby friction is reduced between the 35 said rod and the bearing in which it is mounted to reciprocate.

It is also an object to provide certain 40 details and combinations tending to increase the general efficiency and serviceability of an excavator bucket cleaner mechanism of this particular character.

To the foregoing and other useful ends my invention consists in matter hereinafter set forth and claimed.

In the accompanying drawings:—Figure 45 1 is a side elevation of the upper portion of the boom and system of excavating buckets of a trenching machine having a bucket cleaner mechanism embodying the principles of my invention. Fig. 2 is a sectional view of the apparatus shown in Fig. 1, on a larger scale, the section being taken approximately on line 2—2 in Fig. 4. Fig. 3 is a detail section on line 3—3 in Fig. 2. Fig. 4 is a front elevation of the apparatus

shown in Fig. 2, certain portions thereof being broken away for convenience of illustration, and looking at the said apparatus in a direction at right angles to the angle of inclination thereof. Fig. 5 is a detail section on line 5—5 in Fig. 2. Fig. 6 is a detail section on line 6—6 in Fig. 2.

As thus illustrated, my invention comprises a beam A having its upper end hung on a bracket *a* suitably supported on the horizontal and transverse sprocket shaft B, 65 which latter is in turn supported upon the machine body C in any desired manner. The said beam is adapted to swing on the said shaft, is suitably pivoted with braces *a*¹, *a*², *a*³ and *a*⁴ to provide a swinging or tilting digging frame, and is disposed in position to extend downward and into the trench cut by the machine, as the said body moves slowly forward. For this purpose the said shaft is provided with a pair of sprocket 70 wheels *b*, which are suitably spaced apart, and which are equipped with sprocket chains *b*¹ of any suitable character. These chains, it will be understood, are endless in character, and are supported by similar 75 sprockets (not shown), mounted at the lower end of the beam. The buckets *b*² are rigidly secured by bracket plates *b*³ to the links of the chains, each bucket being open at front and rear and provided with a 80 curved side or front plate *b*⁴, as well as cutters *b*⁵ of any suitable character. With this construction, each bucket tilts upside down, as it travels over said sprocket wheels, in the manner shown in Fig. 2, and at this time 85 the bucket is open at its lower side, whereby the load is automatically discharged. This is all well known construction and will be readily understood.

The cleaner D is preferably in the form 90 of a plate adapted to scrape the inner surface of each bucket, being disposed substantially over the shaft B, whereby it forces the load out of each bucket. The said cleaner is fixed on the upper end of an arm 100 *d*, which latter is pivoted at *d*¹ to the bracket arm *a* of the beam, whereby the said cleaner is supported for movement about a horizontal axis extending parallel with said shaft. The arm *a* may be connected with the beam A in any suitable manner, and has a bearing for the shaft B 105 as shown. A link *d*² has its upper end piv-

oted at d^3 to the lower end of the arm d , and has its lower end pivotally connected at d^4 with the upper end of the vertically disposed and endwise movable rod d^5 , whereby a jointed connection is provided between said rod and arm. The said rod reciprocates endwise in a bearing d^6 secured to the beam, and is subject to the pull or tension of a compression spring d^7 interposed between said bearing and the shoulder d^8 on the end of said rod. In this way, and by the series of connections thus provided between the cleaner and said spring, the latter yieldingly holds the former in operative position. In other words, the spring d^7 is compressed to some extent, depending upon the resistance offered by the load, as soon as a loaded bucket strikes the cleaner. Also, this arrangement makes it possible for the edge of the cleaner to bear hard against the curved inner surface of the bucket, so that even without a load in the bucket the spring will be slightly compressed as the curved surface of the bucket forces the cleaner slightly forward. The cleaner is released at the rear end of the bucket, and the load is discharged downward and suitably taken care of by other means. To prevent side thrust on the rod d^5 , and undue friction where it passes through the bearing d^6 , a link d^9 is interposed between the pivotal joint d^4 and bracket support a , being pivoted to the latter. If desired, there may be two of these links d^9 , disposed at opposite sides of said bracket, thus insuring greater stability and certainty of operation. The link d^9 , or pair of links, as the case may be, prevents the link d^2 from pulling sidewise on the rod d^5 , holding the latter to practically a straight endwise movement. Thus the spring d^7 moves the rod d^5 back and forth in practically a straight line, causing the latter to resist by practically a straight pull the forward movement of the cleaner whenever the latter strikes the bucket. As stated, this prevents the rod from binding in the bearing d^6 , and prevents undue wear and friction at this point in the mechanism. As shown, and as indicated more clearly in Fig. 4, the said cleaner and links d^2 and d^9 are disposed between the sprocket wheels b , and between the sprocket chains b^1 , the latter being tied together by the bodies of the buckets. Any suitable arrangement can be employed for driving the shaft B , as, for example, a sprocket chain E supported by the sprocket wheel e on the said shaft. The buckets, of course, travel upward in the direction indicated by the arrows in Figs. 1 and 2, turning upside down as they pass over the sprockets at the upper end of the beam; then the buckets descend on the other side of the beam in the direction indicated by the arrows. Thus the buckets are effec-

tively cleaned at the point of discharge, and the cleaner mechanism is held firmly and steadily in place, by the link arrangement shown and described, whereby the operation of the spring controlled elements is smooth and practically without any binding action, and without undue wear or friction. This enables the cleaner to yield readily, each time it encounters a loaded bucket, without having to overcome practically anything more than the tension or resiliency of the spring.

What I claim as my invention is:—

1. An excavator comprising a traveling bucket, a support, a bucket cleaner pivoted on said support, a sliding element, a link connecting said element with the cleaner, said link having one end pivoted on the cleaner and the other end pivoted on said element, a spring for yieldingly holding said cleaner in the path of the bucket, applied to said element, and a connection between said element and support, serving to counteract side thrust on said element by said link. 80

2. An excavator comprising a traveling bucket, a support, a bucket cleaner pivoted on said support, a sliding element, a link connecting said element with the cleaner, a spring for yieldingly holding said cleaner in the path of the bucket, applied to said element, and a connection between said element and support, serving to counteract side thrust on said element by said link, said connection having a link pivoted at one end on said support, and pivotally connected at its 95 other end with said element.

3. An excavator comprising a traveling bucket, a support, a bucket cleaner pivoted on said support, a sliding element, a link connecting said element with the cleaner, a spring for yieldingly holding said cleaner in the path of the bucket, applied to said element, and a connection between said element and support, serving to counteract side thrust on said element by said link, sprockets at each side of said cleaner, chains on said sprockets, and means for rigidly connecting said bucket with a link of each chain. 105

4. An excavator comprising a traveling bucket, a pivoted cleaner disposed in position to pass through the bucket, a rod mounted to slide endwise, a link connecting the rod with said cleaner, and a spring for yieldingly holding said cleaner in normal 115 position, applied to said rod.

5. An excavator comprising a traveling bucket, a pivoted cleaner disposed in position to pass through the bucket, a rod mounted to slide endwise, a link connecting the rod with said cleaner, and a spring for yieldingly holding said cleaner in normal 125 position, applied to said rod, a support, and a link connection between said support and rod.

6. An excavator comprising a traveling bucket, a pivoted cleaner disposed in position to pass through the bucket, a rod mounted to slide endwise, a link connecting the rod with said cleaner, and a spring for yieldingly holding said cleaner in normal position, applied to said rod, a support, and means for controlling the action of said link and rod, pivoted on said support.
- 10 7. An excavator comprising a traveling bucket, a pivoted cleaner disposed in position to pass through the bucket, a rod mounted to slide endwise, a link connecting the rod with said cleaner, and a spring for yieldingly holding said cleaner in normal position, applied to said rod, a sprocket at each side of said cleaner, chains on said sprocket, means for securing the bucket to said chains, and means for controlling the
- 15

action of said rod and link, disposed between said chains.

8. An excavator comprising a traveling bucket, a pivoted cleaner disposed in position to pass through the bucket, a rod mounted to slide endwise, a link connecting the rod with said cleaner, and a spring for yieldingly holding said cleaner in normal position, applied to said rod, said cleaner having a plate which passes through the bucket, and means whereby the bucket is turning upside down during the operation of said cleaner.

Signed at Chicago, Illinois, this 26th day of December, 1913.

FREDERIC E. BAGER.
